[57] CLAIM

The ornamental design for a toy truck, substantially as shown and described.

DESCRIPTION

FIG. 1 is a left side elevational view of a toy truck showing our new design;

FIG. 2 is a top plan view thereof;

FIG. 3 is a bottom plan view thereof;

FIG. 4 is a right side elevational view thereof;

FIG. 5 is a front elevational view thereof;

FIG. 6 is a rear elevational view thereof; and

FIG. 7 is a left side elevational view of the toy truck which is similar to FIG. 1, but showing the truck in a slightly different condition.

FIG. 2

FIG. 6

FIG. 5
